VALVE FOR FLUID PRESSURE ACTUATED MOTORS

Filed Feb. 6, 1922.

BY his ATTORNEYS *Frank Johnson* *Ward & Darby* Inventor

Patented May 28, 1929.

1,714,910

UNITED STATES PATENT OFFICE.

FRANK JOHNSON, OF GLEN RIDGE, NEW JERSEY, ASSIGNOR TO NATIONAL PNEUMATIC COMPANY, OF NEW YORK, N. Y., A CORPORATION OF WEST VIRGINIA.

VALVE FOR FLUID-PRESSURE-ACTUATED MOTORS.

Application filed February 6, 1922. Serial No. 534,598.

This invention relates to valves, and particularly valves of the pneumatic type which are employed for controlling door motors of the pneumatic type.

5 The object of the invention is to provide a valve of the foregoing character which is simple in structure, efficient in operation, and economical of manufacture.

A further object of the invention is to provide a valve of this character which will at all times be at one or the other limit of its movement, and hence is incapable of assuming at any time an intermediate position.

A further object of the invention is to provide a valve, which, due to its inherent characteristics as above set forth, will not permit the motor from becoming operative due to leakage in the pneumatic supply line blowing out of a gasket or other failure in the equipment.

20 Other objects of the invention will appear more fully hereinafter.

The invention consists substantially in the construction, combination, location, and relative arrangement of parts, all as will be more 25 fully hereinafter set forth, as shown in the accompanying drawings, and finally pointed out in the appended claims.

Referring to the drawings,—

Fig. 1 is a view in section of a motor valve 30 embodying my invention.

Fig. 2 is a sectional view taken on the line 2, 2, Fig. 1, looking in the direction of the arrows.

Fig. 3 is a sectional view taken on the line 35 3—3 of Fig. 1.

The same part is designated by the same reference character wherever it occurs throughout the several views.

In the door operating art, and particularly 40 the fluid pressure actuated motor art, employed for door operation, difficulty has heretofore been encountered, due to the valve controlling the door motor sometimes stopping at an intermediate position, so that while the door is apparently securely closed, yet the valve is in such a position that pressure is slowly leaking into the motor on the opening end of the motor piston, and the door creeps open while the train is in motion and a passenger is apt to fall through the doorway and encounters serious injury.

It has been found advisable and necessary in the electric control of doors on cars and the like, to use a form of control where a 50 momentary touch on the opening or closing

button will cause the valve to move into reverse position, and so open or close the door, the valve usually employed being a balanced valve that will stay in whatever position it is placed in, and it is moved by momentarily 60 varying the air pressure at one end or the other, and so obtaining a difference of pressure on the piston ends of the valve. It occasionally happens that this momentary variance is performed so rapidly and ceases so 65 quickly that its cessation catches the valve in an intermediate position, so that instead of one end of the door motor being freely open to pressure and the other end being freely open to exhaust, the two ends are on the hair 70 line of being connected to either pressure or exhaust, and the door is in an unstable and dangerous situation.

It is among the special purposes of my present invention to provide a valve which at 75 no time can assume an intermediate position. In other words, to provide a valve which, irrespective of external conditions, will at all times maintain a position at one limit of its movement, for example, the position corresponding to the door closed position of the motor, except when the valve is maintained in the other limit of its position. In general terms my invention comprises a double differential valve, and while its adaptability for 80 use in connection with door motors of the pneumatic type has rendered the foregoing illustration thereof an important application of my invention, I wish it to be understood that I do not desire to be limited or restricted in this respect, as the valve of my invention may be employed in connection with any instrumentality to be controlled where a non-intermediate position of the control valve is 85 desired.

95 Referring to the drawings, I have shown the valve of my invention employed in connection with magnet valves for controlling the exhaust of fluid pressure, and in one form of my invention I attain the objects of my invention as hereinabove outlined by the provision of what will be apparent to be a double differential type of motor valve. I have shown the valve of my invention controlled by the standard type of magnet valves commonly employed today in connection with 100 electric control of fluid pressure actuated motors for actuating doors. Referring particularly to Fig. 1, reference numeral 1 designates the casting of the motor valve, which 105

consists essentially of two cylinders 2 and 3, of relatively different diameter, in which cylinders operate pistons 4 and 5, likewise of relatively different diameter, which pistons 5 are joined together, for example, by a rod 6 of reduced diameter. The diameter of the connection between the pistons, 2 and 5, may be of any suitable size, within, of course, the limits of the size of the motor valve. However, I employ the portion 8 thereof of substantially the same size as the piston 4 with the portion 6 thereof greatly reduced to permit valve slide 7 to be positioned between the piston 4 and the portion 8, so that upon movement of the pistons 4 and 5 the valve slide 7 is shifted as is well understood in the art. The connection between the pistons 4 and 5 likewise includes a relatively large piston 9 which operates in a relatively larger opening and when in its extreme position to the right it seats against the leather gasket 10. The piston 9 is cut away, as illustrated at 11, on its right hand face to form substantially a cup-shaped structure, the purpose of which will be more fully hereinafter discussed. Fluid pressure is admitted to the motor valve from any suitable source through connection 12 provided therefor. The fluid pressure is at all times therefore in the valve motor, and has free access against the piston 5 of smaller diameter, and likewise against piston 4 of relatively larger diameter. The outer end of piston 5 is always open to atmosphere through opening 20, and the outer end of piston 4 is normally open to atmosphere through the magnet valve at that end being deenergized, so that the difference in diameter of the two pistons will always hold the valve securely in the position shown, and the valve could not be retained at any intermediate position. Consequently it will be seen that the structure will be in the position shown in the drawing, and normally will be retained in that position at all times. This position is the door closed position and by the term "normally" as herein used is meant said door closed position. It will readily be seen therefore that if it is desired to open the door, or, in other words, to shift the valve slide 7 by operation of the pistons 4, 5, towards the right, all that is necessary to be done is to supply fluid pressure behind the piston 4. If pressure is supplied behind piston 4, then, in that event, the assembly moves to the right. The progress of piston 5 in its cylinder 3 is unimpeded inasmuch as the cylinder is open through exhaust port 20 to the atmosphere.

I will now describe the instrumentalities employed in accordance with my invention for controlling the valve motor. In the first place, referring particularly to cylinder 3, I provide an annular recess 21 provided with a perforation or perforations 22 therein opening into the cylinder 3, as clearly shown.

The annular recess 21 is in communication through a passage 23 formed in the casting 1 with a port 24 controlled by a control device, for example, magnet valve 25. Another port 26, likewise controlled by the control device 25 is in communication through a passage 27 formed in the casting 1, which passage terminates in the central chamber. At the opposite end of the valve motor a similar port 24^a is provided in the cylinder 2 behind the piston 4. This port 24^a is similarly controlled by a control device such as the magnet valve 25^a, which also controls a port 26^a which is in communication with the pressure chest of the motor valve through passage 27^a in casing 1. The magnet valves 25 and 25^a, employed in accordance with my invention, are of identical construction, and while the valve 25 is the only one shown with reference to ports 24 and 26, it will be understood that the same description will apply to valve 25^a with its ports 24^a and 26^a. In the arrangement shown magnet valve 25 consists of the usual magnet for controlling the stem 30 which operates in the usual manner common to magnet valves, and carries thereon valves 31 and 32 adapted to seat respectively on valve seats 33 and 34. When valve 31 is on its seat 33, valve 32 is off of its seat 34. A spring 35 bearing against the lower end of the valve head normally maintains the valve 32 seated and valve 31 unseated when the magnet valve is deenergized. Port 26 communicates with the passage controlled by valve 32 so that when valve 32 is unseated and valve 31 is seated, communication is established between port 26 and port 24. When, however, valve 32 is seated and valve 31 is unseated, this communication is shut off and port 24 is in communication past valve 31 to open atmosphere through exhaust port 36. It will be understood from the foregoing explanation that valve 25^a of similar construction controls ports 24^a and 26^a, so that when the magnet valve is deenergized port 26^a is closed to communication, whereas port 24^a is open to exhaust. When, however, magnet valve is energized port 24^a is closed to exhaust and pressure fluid is allowed to flow from the pressure chest of the motor valve through connection 27^a, port 26^a, through magnet valve to port 24^a, into the portion of the cylinder 2 behind the piston 4, and thereby operate the motor in the manner hereinbefore described. Upon this operation, as hereinbefore described, the motor moves from the position shown in Fig. 1 to its full position to the right, no pressure opposition being afforded to the piston 5 because of the exhaust port 20. As soon as the piston 9, however, seats against the end 10 of its cylinder or chamber, piston 5 has uncovered the recess 21, whereby the pressure fluid between the pistons 5 and 9 is permitted to flow through the ports 22, recess 21, passage 23, port 24, and, valve 25 being deenergized, past the valve 31

to exhaust port 36 to open atmosphere. The moment this occurs, the main or differential valve is held over to the right by the pressure of air on the large piston seal 9, so that 5 when the pressure is liberated (in the usual manner) from the outer end of piston 4, the piston still retains its rightward position, because the piston seal 9 is larger than the piston 4, and therefore the difference of pressure 10 is now holding the differential valve on its rightward position. Thus it will be readily seen that the valve motor is maintained at the limit of its movement even when the fluid pressure behind the piston 4 is cut off. When 15 it is desired to shift the valve motor to its other extreme position, it will be apparent that it is merely necessary to energize valve 25 to shut off the communication of port 24 to exhaust and permit pressure fluid from the 20 central chamber to flow through passage 27, port 26, port 24, passage 23, recess 21, perforations 22, behind the piston 9, and thereby the pressure on its two sides as the effective area of the piston 9 is practically equal on 25 both sides with the recess 11 provided therein. As the effective pressure area on the right side of piston 4 and cavity 11 is greater than the effective pressure area on the left side of pistons 9 and 5, it will be apparent 30 that the valve motor will thereupon move towards the left. It will also be apparent that it is impossible to hold the motor at any intermediate point in its movement in either direction. In other words, it is absolutely 35 necessary and essential with this structure that the elements assume their limit position in one direction or the other. By reason of the foregoing construction it will readily be understood that the disadvantages of the present types of valve employed, particularly in 40 door motor control work, are overcome, whereby creeping of the valve is completely eliminated with the danger incident thereto.

It will be noted that at the right hand end 45 of the motor the piston 5 is in effect a double piston structure. This is provided to prevent leakage of the actuating pressure should pressure be admitted to recess 21 when the valve motor is at its extreme left position.

Many modifications and changes in details 50 will readily occur to persons skilled in the art without departing from the spirit and scope of my invention as defined in the claims.

But having now set forth the object and nature 55 of my invention, and having shown and described a structure embodying the principles thereof, what I claim as new and useful and of my own invention and desire to secure by Letters Patent is,—

1. A fluid pressure actuated valve comprising 60 differential cylinders, pistons operating therein, and connected together to move in unison, an auxiliary piston of larger diameter than the others and connected to move with said pistons, means for balancing the

pressure on opposite sides of said auxiliary piston except when at one limit of movement of said pistons, and means for exhausting the pressure behind one face of said auxiliary piston when at that limit of movement of 70 said pistons whereby said auxiliary piston is restrained at said limit.

2. A fluid pressure actuated valve comprising 75 differential cylinders, pistons operating therein, and connected together to move in unison, an auxiliary piston of larger diameter than the others and connected to move with said pistons, means for balancing the pressure on opposite sides of said auxiliary piston except when at one limit of movement 80 of said pistons, means for exhausting the pressure behind one face of said auxiliary piston to prevent its return when at that limit of movement of said pistons, and fluid pressure means for controlling the movements of said 85 pistons.

3. A fluid pressure actuated valve comprising 90 differential cylinders, pistons operating therein, and connected together to move in unison, an auxiliary piston of larger diameter than the others and connected to move with said pistons, means for balancing the pressure on opposite sides of said auxiliary piston except when at one limit of movement 95 of said pistons, means for exhausting the pressure behind one face of said auxiliary piston to prevent its return when at that limit of movement of said pistons, and electrically controlled fluid pressure means for controlling the movements of said pistons. 100

4. A fluid pressure actuated valve comprising 105 differential cylinders, pistons operating therein, and connected together to move in unison, a device to be moved controlled by the movement of said pistons, means for normally maintaining the space behind said pistons open to exhaust, an auxiliary piston of larger diameter than the others and connected to move with said pistons, means for balancing the pressure on opposite sides of said auxiliary piston except when at one limit of movement of said pistons, and means for exhausting the pressure behind one face of said auxiliary piston to prevent its return when at 110 that limit of movement of said pistons. 115

5. A fluid pressure actuated valve comprising 120 differential cylinders, pistons operating therein, and connected together to move in unison, a device to be moved controlled by the movement of said pistons, and means for normally maintaining the space behind said pistons open to exhaust, an auxiliary piston of larger diameter than the others and connected to move with said pistons, means for balancing the pressure on opposite sides of said auxiliary piston except when at one limit of movement of said pistons, and means for exhausting the pressure behind one face of said auxiliary piston to prevent its return when at 125 that limit of movement of said pistons, and 130

fluid pressure means for controlling the movements of said piston.

6. A fluid pressure actuated valve comprising differential cylinders, pistons operating therein, and connected together to move in unison, a device to be moved controlled by the movement of said pistons, and means for normally maintaining the space behind said pistons open to exhaust, an auxiliary piston of larger diameter than the others and connected to move with said pistons, means for balancing the pressure on opposite sides of said

auxiliary piston except when at one limit of movement of said pistons, and means for exhausting the pressure behind one face of said auxiliary piston to prevent its return when at that limit of movement of said pistons, and electrically controlled fluid pressure means for controlling the movements of said pistons.

In testimony whereof I have hereunto set my hand on this 19th day of January A. D., 1922.

FRANK JOHNSON.
